US00D998139S

(12) **United States Design Patent** (10) Patent No.: **US D998,139 S**
Barlow et al. (45) Date of Patent: ** Sep. 5, 2023

(54) **PLENUM AND SEAL ASSEMBLY FOR PATIENT INTERFACE**

(71) Applicant: **ResMed Pty Ltd**, Bella Vista (AU)

(72) Inventors: **Adam Francis Barlow**, Sydney (AU); **William Laurence Hitchcock**, Sydney (AU); **Rupert Christian Scheiner**, Sydney (AU); **Gerard Michael Rummery**, Woodford (AU)

(73) Assignee: **ResMed Pty Ltd**, Bella Vista (AU)

(**) Term: **15 Years**

(21) Appl. No.: **29/716,955**

(22) Filed: **Dec. 13, 2019**

Related U.S. Application Data

(60) Division of application No. 29/680,684, filed on Feb. 19, 2019, now Pat. No. Des. 873,993, which is a continuation of application No. 29/581,879, filed on Oct. 24, 2016, now Pat. No. Des. 849,241, which is a division of application No. 29/479,487, filed on Jan. 16, 2014, now Pat. No. Des. 771,238.

(57) **CLAIM**

The ornamental design for a plenum and seal assembly for patient interface, as shown and described.

DESCRIPTION

FIG. 1 is a perspective view of a plenum and seal assembly for patient interface showing a first embodiment according to our new ornamental design;

FIG. 2 is an enlarged perspective view thereof in isolation;

FIG. 3 is a front view thereof;

FIG. 4 is a rear view thereof;

FIG. 5 is a bottom view thereof;

FIG. 6 is a top view thereof;

FIG. 7 is a right side view thereof;

FIG. 8 is a left side view thereof; and,

FIG. 9 is another perspective view thereof.

The broken lines in FIG. 1 represents environmental subject matter that forms no part of the claimed design. All other broken lines represent portions of the plenum and seal assembly for patient interface that form no part of the claimed design.

1 Claim, 5 Drawing Sheets
